(57) **CLAIM**

The ornamental design for nose pad for eyewear, as shown and described.

DESCRIPTION

FIG. 1 is a perspective view of a nose pad for eyewear according to one embodiment of the present invention;

FIG. 2 is a front elevation view of the nose pad for eyewear shown in FIG. 1;

FIG. 3 is a rear elevation view of the nose pad for eyewear shown in FIG. 1;

FIG. 4 is a bottom plan view of the nose pad for eyewear shown in FIG. 1;

FIG. 5 is a top plan view of the nose pad for eyewear shown in FIG. 1;

FIG. 6 is a right side elevation view of the nose pad for eyewear shown in FIG. 1;

FIG. 7 is a perspective view of nose pads for eyewear according to another embodiment of the present invention;

FIG. 8 is a front elevation view of nose pads for eyewear shown in FIG. 7;

FIG. 9 is a rear elevation view of nose pads for eyewear shown in FIG. 7;

FIG. 10 is a bottom plan view of nose pads for eyewear shown in FIG. 7;

FIG. 11 is a top plan view of nose pads for eyewear shown in FIG. 7; and,

FIG. 12 is a right side elevation view of nose pads for eyewear shown in FIG. 7, the left side elevation view being a mirror image thereof.

The broken lines shown herein are for illustrative purposes only and form no part of the claimed design.
